(57) **CLAIM**

The ornamental design for a bottle, as shown and described.

DESCRIPTION

FIG. 1 is a perspective view of a bottle, embodying our new design;

FIG. 2 is a front view thereof, the rear view being a mirror image thereto;

FIG. 3 is a right side view thereof, the left side view being a mirror image thereto;

FIG. 4 is a top view thereof; and,

FIG. 5 is a bottom view thereof.

The broken showing of the pump cap, neck threading and bottom portions are included for the purpose of illustrating environment and form no part of the claimed design.
